United States Patent Office.

W. M. WOOD, OF OWING'S MILLS, MARYLAND.

Letters Patent No. 91,584, dated June 22, 1869.

IMPROVEMENT IN BOAT-DETACHING APPARATUS.

The Schedule referred to in these Letters Patent and making part of the same.

To all whom it may concern:

Be it known that I, W. M. WOOD, a resident of Owing's Mills, in the county of Baltimore, in the State of Maryland, have invented a new and improved Apparatus for Detaching Boats; and I do hereby declare that the following is a full and exact description thereof.

The nature of my invention consists in a bar running through the centre of the boat, and having a projection at each end, over which hook curved links, which are made fast to the bottom of the "falls." The bar revolves in bearings at each end, and it is turned, and held in position by a lever placed on the bar at the after thwart.

When it becomes necessary to detach the boat, it is done by depressing the lever, which causes the bar to revolve, thus throwing the points of the projections up, and allowing the links to slip off.

The ends B of the bar A are made separately, each with the projection c forged upon it. The diameter of these ends is greater by about one-third than that of the balance of the bar A, and the projections are about twice the diameter of the end, B, in length, and may be made to taper from base to top. They are forged to the ends perpendicularly to their axes, and about four inches or other suitable distance from the extreme end of the bar A when the ends B are attached.

On each side of the projection c, the end, B, is turned down to journals d e, of about the same diameter as the balance of the bar A.

The end journals d work in bearings f, made fast to the stern-post g and stern-post h, and the journals e work in bearings i in the heads j of the vertical braces D, which are composed of metal of suitable strength, and have each a foot, k, to secure the brace to the bottom of the boat.

When the ends B are completed, the braces D should be placed on the journals e, and the ends l welded to the ends O of the end-piece B, which should be of metal or other suitable material of requisite strength and length. This welding should be so done that the projections c shall lie in the same plane.

A lever, I, is attached to the bar A, of such length as to suit the depth of the boat, and should be securely affixed to the bar A by either keying or weld-

ing, and in such position that when it is horizontal the projections c will incline downward, on the opposite side of the bar A, at an angle of about seventy degrees, (70°.)

The bar A may be either above or below the thwarts, and should be placed immediately above the longitudinal line of the centre of gravity of the boat, and, in a long boat, should be enclosed by small iron straps, to prevent lateral motion.

The hooks s are each formed of a metal link, of sufficient strength to bear the weight of boat when loaded or light, having its lower end, z, open, and curved outward and upward, in such manner that its interior upper curve shall conform to the circumference of the end, B, of the bar A.

The middle part of the link is closed. The other end, y, is open, to receive a hook or rope.

Blocks F are placed under each end of the bar, for the points of the projections c to rest upon when the lever I is secured in its place against the under side of the aft thwart. These blocks will prevent the hooks s from being attached on the wrong side of the bar A, and from detaching or dropping off, should the strain upon them be relieved prematurely.

Operation.

Press down the lever I until the projections c stand at right angles to the keel of the boat. Place the hooks s over, and enclosing them. Return the lever I to its position against the thwart z, and the attachment is effected.

To detach, press down the lever I until the projections c stand at an angle of about seventy degrees (70°) to the keel of the boat, whereupon the strain will cause the hooks s to slip off the projections c, and the boat is free.

What I claim as my invention, and desire to secure by Letters Patent, is—

The projections c, the block F, and the hooks s, in combination with the bar A and lever I, arranged and operated for the purpose substantially as described.

W. M. WOOD.
